UNITED STATES PATENT OFFICE.

FERDINAND W. BECKER, OF PHILADELPHIA, PENNSYLVANIA.

BOX OR CASE FOR BOTTLES.

SPECIFICATION forming part of Letters Patent No. 511,672, dated December 26, 1893.

Application filed September 21, 1893. Serial No. 486,127. (No model.)

To all whom it may concern:

Be it known that I, FERDINAND W. BECKER, a citizen of the United States, residing in Philadelphia, Pennsylvania, have invented 5 certain Improvements in Boxes or Cases for Bottles, of which the following is a specification.

The object of my invention is to so construct a box for the transportation of bottles 10 that the same will be lighter than usual, can be readily cleaned, and is not so liable to rot as boxes constructed in the ordinary manner.

This object I attain in the manner herein-after set forth, reference being had to the accompanying drawings, in which—

Figure 1, is a perspective view of a box or case for bottles constructed in accordance with my invention, part of the box being broken away in order to show the interior 20 construction. Fig. 2, is a transverse section of the box; and Fig. 3, is a longitudinal section of the same.

The box comprises the opposite end pieces A A', the opposite sides B B' and a slatted 25 bottom composed of spaced strips *a* suitably secured to the ends A A', the end portions of the box being strengthened, as usual, by enveloping metal bands *b*. The opposite sides B B' of the box do not extend down to the 30 bottom of the same, a space *d* being left at each side of the box adjacent to the bottom so that foreign matters can be readily shaken or washed out of the box, these side openings *d* and the openings between the slats which 35 constitute the bottom of the box providing a ready means of escape for the same. The box has the usual internal rack forming pockets for the bottles, but only the transverse bars *f* of this rack extend to the bottom of 40 the box, the longitudinal bars *g* being less in

depth than the transverse bars so that they do not interfere with the free lateral escape of foreign matters from the box or with the free flow of a stream of water from side to side of the box over the bottom of the same 45 when the box is being washed out. This construction of sides and rack may be adopted in boxes having closed bottoms, but the use of the slatted bottom is preferred, because owing to the amount of material dispensed 50 with in the bottom, rack and sides, the box is lighter than usual and a free circulation of air in all parts of the box is permitted so that rapid rotting due to dampness is prevented.

Having thus described my invention, I 55 claim and desire to secure by Letters Patent—

1. The combination in a box or case for bottles, of the sides discontinued some distance from the bottom of the box so as to form side 60 openings, and a rack having the longitudinal bars likewise discontinued some distance from the bottom of the box so as to provide a free lateral passage from side to side of the box over the bottom of the same, substantially 65 as specified.

2. The combination in a box or case for bottles, of the bottom composed of a series of spaced slats, the sides discontinued some distance from the bottom so as to form side openings, and the rack having the longitudinal bars also discontinued some distance from the bottom of the box, substantially as specified. 70

In testimony whereof I have signed my name to this specification in the presence of 75 two subscribing witnesses.

FERDINAND W. BECKER.
